ATTORNEY

UNITED STATES PATENT OFFICE.

CHARLES E. BRADSHAW, OF WATERBURY, CONNECTICUT, ASSIGNOR TO ROBERT N. BASSETT COMPANY, INCORPORATED, OF SHELTON, CONNECTICUT, A CORPORATION OF CONNECTICUT.

BUCKLE.

1,274,671.

Specification of Letters Patent.

Patented Aug. 6, 1918.

Application filed December 23, 1916. Serial No. 138,544.

To all whom it may concern:

Be it known that I, CHARLES E. BRADSHAW, a citizen of the United States, residing at the city of Waterbury, in the county 5 of New Haven and State of Connecticut, have invented a certain new and useful Improvement in Buckles, of which the following is a specification.

My invention relates to metal mountings 10 for running webbing, but more particularly to buckles of the style which are provided with pivoted levers, and its object is to produce such a buckle in which the lever and frame can be assembled by hand thereby dispensing with the employment of the usual 15 assembling machinery.

I attain these and other objects of my invention in the device set forth in the following description and accompanying drawings in which like reference characters refer to corresponding parts.

In the drawings:

Figure 1 is a front view of my buckle in its open position;

Fig. 2, an enlarged central, vertical, sectional view showing the buckle strung with webbing and in its closed position, and

Figs. 3 and 4, rear and side views showing the parts partially assembled.

The fundamental features of my invention are disclosed and claimed in my application for button clasps filed March 29, 1916, Serial No. 87511. The specific form of my invention disclosed herein is embodied in a buckle made either of sheet metal or wire which is shown mounted on a supporting strap or webbing 2. The buckle may be of any suitable construction provided the hinge connection between the lever and back consists of a pintle bar journaled in a bearing sleeve or sleeves. I prefer, however, to utilize one of the so-called Pellar type which consists of a back or frame 3 to which is pivoted a lever 4. The back 3 is bent up 40 out of a single piece of wire to form a loop having a lower side 5, ends 6, 6' and inwardly projecting pintles 7, 7' which latter may be regarded as the top side. The lower side 5 is provided at its middle portion with 45 a downward projection 8. The lever 4 is preferably made out of sheet metal and is bent to form a front portion 9, a web-gripping member 10 and pintle bearings 11, 11'. The buckle thus far described is one in common use on the market and is merely dis-

closed herein for the purpose of showing how my invention is applied to buckles generally. Immediately beyond and to one side of the pintles 7, 7' the end portions 6, 6' are made thin or flattened as shown at 12, 12'. 60 When the lever 4 is being formed the straps which form the pintle bearings 11, 11' respectively are curled so that their edges 13, 13' are spaced sufficiently from the front portion of the lever to leave slots or openings 14, 14'. To assemble the lever and back they are placed laterally of each other and the flattened portion 12' is passed into the slot 14 in the adjacent pintle bearing 11 as shown in Fig. 3. The flattened portion 12' is then passed entirely through the slot 14 and also through the slots 14' in the opposite pintle bearing 11' so that the parts are brought into the position shown in dotted lines in Fig. 3. During the telescopic action 70 between the parts just described the front of the lever is pressed as close to the bottom side of the back as possible in which position the slots or openings 14, 14' in the pintle bearings are in alinement with flattened portions 12, 12'. After the pintles have been slid into their bearings the lever may be then swung upwardly to the position shown in dotted lines in Fig. 4 in which position the buckle is open and the flattened portions 80 and slots out of alinement. The buckle may now be webbed in any well-known manner, one way being to fold one extremity *k* of the webbing around the lower side 5 of the back and to pass the other extremity upwardly 90 between the lever and back. The buckle may then be closed so that its web-gripping portion 10 engages and co-acts with the lower side 5 of the back to grip the webbing in its adjusted position, as shown in Fig. 2. When 95 the buckle is webbed and closed the lever can not swing close enough to the lower side of the back to bring the flattened portions 12, 12' and the slots 14, 14' into alinement, and for this reason there is no danger of the buckle becoming disassembled after it has once been webbed. I have shown the ends of the back flattened beyond each pintle so that the device may be assembled either from the right or left. It is obvious, however, that it is only necessary to flatten one end of the back in which case the parts would be assembled in one direction only.

While the device above described is the preferred form of my invention yet the same 110

is susceptible to such modification as may come within the scope of the appended claims.

Having now described my invention what I claim and desire to protect by Letters Patent is:

1. A buckle comprising two articulated members and a bearing carried by one of said members having its side provided with an opening from end to end, the other member having a pintle bar journaled in said bearing and a flattened portion to one side of and beyond one end of said pintle bar, the direction of the plane of the said flattened portion being such that the pintle bar can slide into said bearing only when the buckle is not strung with webbing.
- 10 2. A buckle comprising a lever having a bearing which is open on its under side from

end to end and a frame having a pintle bar 20 journaled in said bearing, the said frame having alined flattened portions to one side of and beyond the ends of said pintle bar, the direction of the plane of the said alined flattened portions being such that the pintle 25 bar can slide into said bearing only when the lower portion of the lever is shut down against the lower portion of the frame.

3. A buckle for webbing of the kind which comprises front and back members which 30 may be opened and closed characterized by the fact that the said front and back members may be disassembled by a lateral movement relative to each other when the buckle is closed and not strung with webbing. 35

In testimony whereof I have hereunto set my hand this 29th day of November, 1916.

CHARLES E. BRADSHAW.
